UNITED STATES PATENT OFFICE.

CHARLES E. BROOKS, OF BROOKLYN, NEW YORK.

SPRING-ROLLER.

SPECIFICATION forming part of Letters Patent No. 350,656, dated October 12, 1886.

Application filed May 6, 1886. Serial No. 201,308. (No model.)

To all whom it may concern:

Be it known that I, CHARLES E. BROOKS, of the city of Brooklyn, in the county of Kings and State of New York, have invented a new and useful Improvement in Window-Shade Spring-Rollers, of which the following is a full, clear, and exact description.

Reference is to be had to the accompanying drawings, forming a part of this specification, in which similar letters of reference indicate corresponding parts in all the figures.

Figure 1 is a sectional side elevation of a part of a window-shade spring-roller to which my improvement has been applied. Fig. 2 is an end elevation of the roller. Fig. 3 is an end elevation of the same, the cap being removed. Fig. 4 is a sectional end elevation of the same, taken through the line *x x*, Fig. 1.

The object of this invention is to provide window-shade spring-rollers constructed in such a manner that their revolution will be stopped automatically when the shade has been rolled up to a fixed limit, to prevent disarrangement or breakage of the roller or its fixtures.

25 should the roller be accidentally released.

The invention consists in the construction and combination of various parts of the window-shade spring-roller, as will be hereinafter fully described.

30 A represents a window-shade spring-roller, the spring of which is not shown in the drawings, as there is nothing new in its construction or operation.

B is the shade, which is attached to the roller 35 A in the ordinary manner. In the roller A, preferably at or near one end, is formed a slot, into which may be inserted a case, C, the edges of which are curved to correspond with the surface of the roller A, and its sides are flat to 40 fit into the slot in the said roller.

The case C is made a little longer than the slot in which it is placed, so that its inner end may enter the body of the roller at the inner end of the said slot, to keep the said inner end 45 of the case in place. Upon the outer end of the case C may be formed flanges D, to fit against the end of the roller A, and which are perforated to receive nails or screws to fasten the outer end of the said case in place. The outer 50 end of the case C is further secured in place, and the slotted end of the roller A is held from

spreading by a cap, E, fitted upon the end of the said roller, and which may be secured in place by nails or screws passing through it and into the end or sides of the said roller.

55 The cap E is perforated centrally to receive the rod F, the inner end of which enters a perforation in the body of the roller A at the end of its slot. The rod F is provided with a collar, G, at the outer side of the cap E, and its outer end is flattened to fit into a slot in a bracket, H, attached to the window-easing to support the end of the roller A and hold the rod F from turning with the said roller. The rod F is provided with a screw-thread extending from the collar G nearly to the other end of the said rod, as shown in Fig. 1.

Upon the screw-rod F is placed a nut, I, which is made of such a shape and size that it can readily move longitudinally in the case C, 7c but cannot turn in the said case. The case C strengthens the slotted roller A against the pressure of the nut I as the said nut is turned by the revolution of the said roller.

In adjusting the improved shade-roller for 75 use the screw-rod F is passed through the perforation in the cap E, and the nut I is placed upon the said screw-rod and screwed up against the inner side of the said cap. The case C is then inserted in the slot in the roller A, and 80 the screw-rod F and the nut I are inserted in the said case, and the cap E is secured to the end of the roller A. The shade B is then wound upon the roller A to the point which is desired to be the limit of the upward movement of the 85 said shade, and the roller is secured in its brackets. With this construction, when the shade B is drawn downward, the revolution of the roller A turns the nut I upon the screw-rod F, and causes the said nut to travel toward the inner end of the said screw-rod until, if the shade 90 is drawn down far enough, the said nut strikes against the solid body of the roller A, and the limit of the downward movement of the shade is reached. When the shade B is again wound upon the roller A, the nut I travels outward upon the screw-rod F until the said nut comes in contact with the cap E and the limit of upward movement of the shade is reached. With this construction, should the shade be accidentally released and allowed to run up, the 95 roller A will be stopped when the limit of 100

upward movement is reached, and the end of the said shade cannot pass over the roller, taking the coil out of the spring, and causing the breakage of some part of the fixtures.

5 I am aware that it is not new to employ a contrivance for adjusting the tension of a spring in a window-shade roller, the same consisting of a slotted nut working on a screw, to which latter is also applied the spring, said nut receiving in its slot a guide-rod fixed to said roller.

Having thus fully described my invention, I claim as new and desire to secure by Letters Patent—

In a window shade roller, the combination, with the slotted roller fitted with a case, of the 15 fixed screw with one end journaled in the roller and its other end held fixedly in a bracket, the nut arranged upon said screw within said case, and the cap fitted upon one end of the roller, substantially as and for the purpose set forth.

CHARLES E. BROOKS.
